E. Pelouze, Jr.,
Type Machine.

No. 15,380.

Patented July 22, 1856.

Fig. 1.

UNITED STATES PATENT OFFICE.

EDWARD PELOUZE, JR., OF PHILADELPHIA, PENNSYLVANIA.

IMPROVED VALVE FOR TYPE-CASTING MACHINES.

Specification forming part of Letters Patent No. 15,386, dated July 22, 1856.

To all whom it may concern:

Be it known that I, EDWARD PELOUZE, Jr., of the city and county of Philadelphia and State of Pennsylvania, have invented certain new and useful Improvements in Machines for Casting Type; and I do hereby declare the following to be a full, clear, and exact description of the same, reference being had to the accompanying drawings, making a part thereof, in which—

Figure 1 represents a perspective view of the machine, and Fig. 2 represents a vertical longitudinal section taken through the center of the more immediate operative parts of the machine.

The nature of my invention relates to the combination of a self-acting valve with the nipple of type-casting machines, which by its peculiar construction and operation regulates the flow of metal to the well, as well as its exit through the nipple, and works in concert with the plunger in the well.

To enable others skilled in the art to make and use my invention, I will proceed to describe the same with reference to the drawings.

The machine in construction resembles those in common use; and my invention can be readily added to the present form of machines for casting type with but little expense.

It is unnecessary to describe the process of casting type by means of a pump, as it is well known, and I do not allege to have changed the general principle involved in such machines, but have so improved upon the details of the operation as to remove the most serious objections incident to it—viz., the chilling of the metal at the point of or within the nipple, the reaction upon the metal, which spirts out metal at improper periods, and the entire prevention of the sticking or clogging of the valve or stem in the nipple by leaving them free to move to the volume or force of the metal passing through the ducts.

A represents the bath of metal or melting-pot, of the usual form, in which the type-metal is kept hot by a furnace underneath it. In this pot is a well, B, of cylindrical form, in which a plunger, C, is made to work by means of a lever, D, which has its fulcrum in the standard E, and to one end of which lever

the rod F of the plunger is attached. The plunger C is solid—that is to say, it has no valve or opening in it—and acts as a piston-head in a cylinder.

The well B is formed in a solid piece of metal of a reversed-L form, and in the upper part, G, of said piece of metal is formed a valve-chamber, a, and from this chamber a to a point at or near the bottom of the well is formed a duct or passage, b. The end of the valve-chamber a next the pot is of conical form, so as to furnish a seat for a similarly-formed valve on the stem which plays therein, and an opening of less diameter than the chamber is made from the valve-seat into the pot for the rear part of the valve-stem to work in, as will be presently described.

I is the nipple, formed as shown in the drawings. It has a slightly-tapered hole, c, bored into it to near its point, and from thence a small hole, e, for the metal to pass out of, leaving a shoulder at i of square or nearly square form.

J is a self-acting valve and stem furnished with a conical button or valve, n, which has its seat in the end of the valve-chamber. Behind the button is a stem, m, which fits loosely in the opening o, so as to allow the metal to pass in between the said stem and opening. In front of the button n is a rod, r, which projects into the nipple I, and the end of said rod is square, or nearly so, to fit against the square shoulder i in the nipple when it is driven forward by the action of the plunger. The distance between the button n and the end of the rod or wire r is less than that between the valve-seat and shoulder i, so that as the valve and stem are driven through the valve-chamber it shall open one passage and close the other, and vice versa.

The valve may be said to float in the fluid metal uncontrolled by anything but the inflow and outflow of the metal by the action of the pump. A small delicate spring is attached to the stem m, not to effect it against the flow of metal, but simply to protect the valve from opening by a jar of any kind. When the plunger is raised, the metal passes in between m and o, and, driving the valve and stem forward, closes the exit e and allows the metal to descend through the duct b into the well. When

lowered, the button *n* is driven back against its seat, closing the inlet and opening the exit at *e*, and so on.

Having thus fully described the nature of my invention, I would state that I am aware that a stopper operated by machinery has been used in connection with the nipple of type-casting machines. This I do not claim; but

What I do claim as new, and desire to secure by Letters Patent, is—

In combination with the nipple, the self-acting valve and stopper, made and operating substantially in the manner and for the purpose set forth.

EDWARD PELOUZE, JR.
